A. BERNSTEIN.
MATTRESS.
APPLICATION FILED MAR. 4, 1918.

Patented Oct. 18, 1921.

Abraham Bernstein,
INVENTOR.
By Arthur D. Ewald,
ATTORNEY.

UNITED STATES PATENT OFFICE.

ABRAHAM BERNSTEIN, OF CINCINNATI, OHIO.

MATTRESS.

1,394,061.

Specification of Letters Patent.

Patented Oct. 18, 1921.

Application filed March 4, 1918. Serial No. 220,221.

To all whom it may concern:

Be it known that I, ABRAHAM BERNSTEIN, a citizen of the United States, and a resident of Cincinnati, in the county of Hamilton and State of Ohio, have invented certain new and useful Improvements in Mattresses, of which the following is a full, clear, and exact description, reference being had to the accompanying drawings, forming a part 10 of this specification.

My invention relates to mattresses, and particularly to mattresses in which provision is made for renovation and sanitation.

Mattresses, especially when used by children or persons in poor health, require, in order to be maintained in perfect sanitary condition, to be frequently renovated, and to accomplish this effectively the filling, whether of cotton, felt, hair, or other suitable material, should be removed from the cover or casing, and both parts separately renovated and exposed to the light and air. To accomplish this, in the case of the ordinary tufted mattresses, is a matter of great difficulty and delay, and consequently this highly necessary function is either entirely neglected or only partially, and therefore ineffectually, performed. The provision of a mattress, in which the filling being inserted in sections, may be speedily removed with a minimum of labor is the chief object of my invention.

A further object of my invention is the provision of a mattress having a casing which presents only smooth surfaces to the outside, thus avoiding the usual recesses for the accumulation of dust and vermin found in the ordinary tufted mattresses.

Other objects of my invention will appear from the following detailed description thereof.

In the drawings:

Figure 1 is a perspective of a mattress constructed in accordance with my invention; Fig. 2 is a perspective of one of the filling sections or strips.

The numeral 1 indicates the casing of my new mattress. The said casing is made of ordinary drill or other suitable fabric, and is, when filled, of generally rectangular shape, as shown. Partition strips 2, of the same material, are sewed at intervals be-

tween the upper and lower surface walls 3 and 4. The wall 4 is extended at the ends to provide flaps 5 and 6 to close the ends 55 when the mattress has been filled; the said flaps being either stitched to the wall 3 or laced thereto as may be preferable.

The filling for my new mattress consists of strips of cotton, felt, or other suitable material 7, illustrated in Fig. 2. The strips 7 are provided each with a longitudinal line of stitching 8, centrally located between the sides of the strip. The thread, or cord, used in the stitching, extends beyond the 65 ends of the strip 7, to provide grips 9 and 10, to be used in the insertion and removal of the strip or section, into or from the casing 1. The strips or sections 7 are inserted into the divisions of the casing 1 between the 70 partitions 2 so that the unstitched surfaces of the sections are adjacent the upper and lower walls 3 and 4 of said casing, as illustrated in Fig. 1 of the drawings.

From the foregoing description, the nature and value of my new mattress will be apparent. When the sections 7 have been inserted in the casing 1, the walls 3 and 4 of said casing present smooth surfaces. In order to renovate the mattress it is only 80 necessary to remove the sections 7 by means of one of the end grips 9 or 10. Both casing and filling strips may then be thoroughly cleaned and renovated, after which it is a matter of great simplicity again to assemble 85 the casing and strips and to close the end flaps 5 and 6, when the mattress is again ready for use. Should either casing or one or more of the filling strips become so fouled as to be no longer fit for use the ruined part 90 or parts may be replaced by new parts and a virtually new mattress obtained at a cost greatly less than the original cost of the mattress.

As will be seen, furthermore, a mattress 95 constructed in accordance with the above description, may be conveniently rolled for transportation into much smaller dimensions than is possible in the case of mattresses of ordinary construction, and it is also possible, as is of course obvious, to remove the filling strips from the casing, thus further facilitating the packing of the mattress for transportation.

Having thus described my invention, what I claim as new and desire to secure by Letters Patent is:

In a mattress in combination with a casing having a series of partitions dividing said casing into compartments, of a series of resilient filling strips arranged to fit into said compartments, and a longitudinal line

of stitching in each of said strips, independent of said casing, the ends of said stitching extending beyond the ends of the strips to provide grips whereby said strips may be inserted into and removed from said compartments.

ABRAHAM BERNSTEIN.
